Attorneys.

UNITED STATES PATENT OFFICE.

CHARLES A. BALPH, OF PITTSBURG, AND ELISHA P. S. WRIGHT, OF AVALON,
PENNSYLVANIA.

FIREPROOF FLOOR AND CEILING.

SPECIFICATION forming part of Letters Patent No. 527,042, dated October 9, 1894.

Application filed February 28, 1894. Serial No. 501,106. (No model.)

To all whom it may concern:

Be it known that we, CHARLES A. BALPH, a resident of Pittsburg, and ELISHA P. S. WRIGHT, a resident of Avalon, county of Allegheny, State of Pennsylvania, have invented a new and useful Improvement in Fireproof Floors and Ceilings; and we do hereby declare the following to be a full, clear, and exact description thereof.

10 Our invention relates to the construction of fire-proof floors and ceilings. The fire-proof floor most generally in use to-day is the hollow tile floor composed of either hard or porous tile. The hollow tile 15 floor is dependent on the skill and care of irresponsible workmen who may, or may not, set the arches properly, and accordingly the strength of such a floor is often impaired by poor workmanship. Again, a sudden jarring 20 load may break the key of a flat tile arch and destroy its bond, the result being a caving in of a section of the floor. Furthermore, the hollow tile floor is designed to carry certain loads and cannot be graduated to suit the 25 requirements of particular buildings, the cost of construction being practically the same whether the floor is to be used for a heavy storage warehouse or for light office purposes.

The object of our invention is to provide a 30 fire-proof floor or ceiling which does not require the employment of skilled labor in its construction; one which is not only incombustible in itself, but capable of resisting to the highest degree the effect of heat, and one 35 that will not disintegrate under the combined action of heat and water; one which can be speedily constructed and put into service; one that will prevent the transmission of sound from one story to another, together 40 with certain other advantageous qualities which it is not necessary to enumerate here.

Our invention consists, generally stated, in connecting the floor beams at intervals by means of rods or bars, placing a wire net-work over said bars or rods, and embedding 45 and covering the bars and wire net-work with a strong cement concrete.

Our invention further comprises certain details of construction and combination of 50 parts, all of which will be fully hereinafter set forth and claimed.

To enable others skilled in the art to make

and use our invention, we will describe the same more fully, referring to the accompanying drawings in which—

55

Figure 1 is a cross-section of a portion of a floor and ceiling before the application of the cement to the floor and showing the cemented ceiling. Fig. 2 is a perspective view of a section of the floor and ceiling showing more clearly the construction before the cement is applied to the ceiling. Fig. 3 is a like view showing the cement in place. Fig. 4 is a longitudinal section at right angles to Fig. 1 showing the cement applied to the ceiling 65 and showing the construction before the cement is applied to the floor. Fig. 5 is a like view showing the construction before the cement is applied to the ceiling. Fig. 6 is a view of the finished floor and ceiling, and 70 showing the means of opening communication between the different air spaces, and Fig. 7 is a view of a modified form of bar.

Like letters indicate like parts in each of the figures.

75

In Fig. 1 of the drawings we have represented a portion of a floor in section, *a* designating I-beams arranged at suitable intervals apart and having their ends supported in the ordinary manner.

80

Fitting over the I-beams are the stirrups *b* which straddle said beams and support the bars *c*, said bars being of length corresponding substantially to the space between the I-beams, and *c* extending across from one beam 85 to another and arranged at suitable intervals according to the load they are to carry. By the employment of the stirrups the bars are supported without having to punch holes through the beams to secure the bars thereto 90 by bolts passing through an angle connection on said bars, thus tending to diminish the strength of said beams. The bars *c* are preferably supported on their edges and are formed with the longitudinal ribs *c'*, which 95 serve to aid in supporting the concrete, as will more fully hereinafter appear.

A wire-netting *d* of suitable mesh is supported by the bars *c*, where it is found necessary to sustain the body of concrete between 100 said bars *c*, said wire netting by passing as indicated over these transverse supporting bars enabling them to carry a greater load and to be placed at farther distances apart;

though the transversely extending bars *c* may be employed to support the concrete without the use of the wire netting if desired, the bars being placed nearer to each other.

5 Where a ceiling is desired tie-rods *e* are employed to connect the beams *a*, but said tie-rods are preferably placed as close as possible to the lower flange of the beam, instead of in the center thereof. The tie-rods *e* are brought to perfect tension by the nuts *e'*. A wire-netting *e*² also passes over the tie-rods *e* in the same manner as the wire-netting *d*, above referred to.

As the construction of the ceiling is usually 15 the first step, a temporary platform to support the concrete while it is being laid is first erected. This platform is usually termed by the builder "a centering," and we will designate it by that term throughout the specification and claims. This centering *f* is usually formed of wood and is supported by the rods *g*, said rods *g* in turn being supported by the bolts *h* having the hooked ends *h'*. We prefer to employ pipe for the rods *g*, as 25 they are lighter and more easily handled. The bolts *h* are held at their upper ends within the plates *i*, said plates being bent to engage one of the flanges of the beam *a*. The centering is drawn up into position and held 30 securely in place by means of the nuts *h'* on said bolts *h*, but when it is desired to draw the centering forward to construct another section of ceiling, by removing the nuts *h'* the plates *i* can be moved along the beam, while by striking 35 the upper end of said bolts *h* they can be withdrawn from the concrete from below, and moved forward together with the centering supported thereby, when said centering is again erected in position as before. Before 40 drawing up the centering to position, however, the bottom faces of the lower flanges of the beams *a* are protected by strips of asbestos or like incombustible material *j*. The edges *j'* of the asbestos strips *j* are turned up 45 slightly so that when the concrete is packed the edges will be embedded therein and the asbestos securely held in place flush with the ceiling. The centering *f* having been drawn up to position and the wire-netting having 50 been passed over the tie-rods *e*, a concrete, such as Portland cement and crushed furnace slag of the proper consistency, is thrown upon the wire-netting *e*² and then packed down through the said netting onto the centering 55 which gives the concrete a smooth even surface. The concrete is laid on thick enough to embed the tie-rods *e*. As the ingredients which compose the concrete are the products of the most intense heat, the result is a thoroughly fire-proof and non-conduction ceiling, which is entirely independent of the floor. The wire-netting *e*² sustains and imparts tensile strength to the concrete, and transmits the weight to the tie-rods *e*, while the asbestos under the beams *a* furnishes a thorough 65 protection from heat where most needed.

In constructing the floor a centering *k* is

employed, said centering being supported in the same manner as the centering *f*, namely, by the use of bolts *l* which support the rods *m*, said bolts being secured to plates *n* by nuts *o*. The plates *n* engage the upper flange of the beams *a* in the same manner as the plates *i*. The centering *k* is provided with the sides *k'* so that when said centering *k* is in position 75 a space will be left between the web of the beams *a* and the sides *k'* for the reception of the concrete to protect said beams.

The centering *k* having been arranged at the proper height to give the proper thickness to the floor, and the bars *c* and wire-netting *d* having been arranged as above described, a concrete similar to that before described is thrown onto the netting and packed down through said netting onto the surface 85 of the centering *k*, and at the same time into the space between the sides *k'* of the centering and the webs of the beams *a*. Sufficient concrete is employed to completely cover and embed the bars *c* as well as the top of the 90 beams *a*.

The ribs *c'* of the bars *c* serve to aid in supporting the concrete, while at the same time they increase the strength of said bars. The concrete is omitted, however, just around the 95 bolts *h* and *l* and the supporting plates *i* and *n* to allow for the removal of the nuts thereon and the loosening of said bolts so that they can be withdrawn from below when the centering is withdrawn. After the withdrawal of 100 the bolts and the removal of the plates *i*, *n*, the space around said bolts and plates can then be filled up with concrete uniformly with the rest of the floor.

The steel bars *c* transmit their load to the 105 beams by means of the stirrups *b* and practically take the place of small beams, as they are equivalent in carrying power, the weight of the flanges being saved, as the concrete takes the place of the flanges, bracing the 110 bars laterally so that the full carrying power of the web is secured. The bars *c* are even stronger than the beams are proportionately, as the concrete adds a greater strength to the bar than does the flange to a beam, the bars 115 being embedded in and surrounded by a solid mass, which in time becomes as stone, and absolutely prevents any tendency to side deflection or buckling.

In Fig. 7 we have shown a modified form of 120 the bars for supporting the floor. This bar *s*, instead of having longitudinal ribs thereon, is formed with the projections *t* which serve to catch the concrete and support the same.

We do not confine ourselves to any particular form of projections on the bars, as they may vary as desired. Any kind of roughened faces on said bars which will act to catch and hold the concrete may be employed. If the bars are arranged sufficiently near to 130 one another the net-work covering may be omitted.

The concrete used for this work is quick-setting, so that the centering can be moved

in a few hours and the next section may then be constructed. The floor and ceiling are put in by sections, beginning at one wall and building out therefrom to the opposite wall, 5 but at the last section a light sheet iron centering is used which remains permanently in the structure.

The floor is brought up level with the beams *a* and within the concrete are the floor strips *p*, in case a wooden floor is to be employed; 10 but in case an asphalt, tile, or cement topping is to be applied the strips *p* are omitted, while the concrete forms an excellent base for any such topping of asphalt, tile, or cement.

15 The space *q* between the floor and ceiling forms a sound deadening chamber, while at the same time, by opening communication between the several air spaces, the air may be circulated throughout the building and may 20 be employed for ventilating rooms. To form this communication between the air spaces *q* we employ the conduits *r* which may be formed of tin or other suitable material, said conduits extending from one air space up 25 over the beam into the next one and so on throughout the building.

The features of advantage to the builder which may be mentioned are these: The absence of great quantities of tile which greatly 30 obstruct a building in course of erection and interfere with the progress of other work. Our floor can be put up quickly without obstructing the building and can be used immediately after construction. It leaves a floor 35 as perfectly level as a cement floor in a cellar. By having the floor entirely independent from the ceiling a heavy load carried by the floor puts no strain whatever on the ceiling. Any sagging of the floor will not affect the 40 ceiling. Holes can be cut through the floor at any point without impairing its strength, while at the same time pipes, conduits, &c., can be conducted through the air spaces between the floor and ceiling, without the labor 45 and inconvenience of embedding them in the floor filling. Furthermore, our construction tends to tie the building together, the floor being a homogeneous mass, which adds strength to the entire structure.

50 What we claim as our invention, and desire to secure by Letters Patent, is—

1. In a floor or ceiling, the combination with the beams, of metal bars connecting said beams, an open-work covering extending over 55 said bars, and concrete completely embedding said bars and open-work covering, substantially as and for the purposes set forth.

2. In a floor or ceiling, the combination with the beams, of metal bars connecting said 60 beams, said bars being supported by hangers on said beams, an open-work covering extending over said bars, and concrete completely embedding said bars and open-work covering, substantially as and for the purposes set 65 forth.

3. In a floor or ceiling, the combination with the beams, of hangers straddling said beams, metal bars supported thereby, an open-work covering extending over said bars, and concrete completely embedding said bars and 70 open-work covering, substantially as and for the purposes set forth.

4. In a floor or ceiling, the combination with the beams, of metal bars connecting said beams, said bars being supported on their edges, an open-work covering extending over 75 said bars, and concrete completely embedding said bars and open-work covering, substantially as and for the purposes set forth.

5. In a floor or ceiling, the combination with the beams, of bars having longitudinal ribs formed thereon connecting said beams, said bars being supported on their edges, an open-work covering extending over said bars, and concrete embedding said bars and 85 open-work covering, substantially as and for the purposes set forth.

6. In floor or ceiling construction, the combination with the beams, of a centering suspended therefrom, said centering having side 90 pieces, substantially as and for the purposes set forth.

7. The combination with the beams, of bars connecting the upper portions of said beams, an open-work covering extending over said 95 bars, concrete embedding said bars and open-work covering, bars connecting the lower portions of said beams, an open-work covering extending over said bars, and concrete embedding said bars and open-work, substantially as and for the purposes set forth.

8. The combination with the main supporting beams, of solid metal supporting bars of length corresponding substantially to the space between the beams and extending transversely of and connected to the beams, said 105 bars being supported on their edges, and a filling of concrete completely surrounding said bars and supported thereby, substantially as and for the purposes set forth.

9. The combination with the main supporting beams, of solid metal supporting bars of length corresponding substantially to the spaces between the beams and extending transversely of and connected to the beams, 115 said bars being supported on their edges and having longitudinal ribs on their side faces, and a filling of concrete completely surrounding said bars and supported thereby, substantially as and for the purposes set forth.

In testimony whereof we, the said CHARLES A. BALPH and ELISHA P. S. WRIGHT, have hereunto set our hands.

CHARLES A. BALPH.
ELISHA P. S. WRIGHT.

Witnesses:

ROBT. D. TOTTEN,
J. N. COOKE.
